UNITED STATES PATENT OFFICE.

WALTER LUTTRINGHAUS, OF MAYWOOD, ILLINOIS.

DESIGN FOR A TEA-KETTLE.

51,144.

Specification for Design.

Patented Aug. 14, 1917.

Application filed January 27, 1917. Serial No. 145,006. Term of patent 14 years.

To all whom it may concern:

Be it known that I, WALTER LUTTRINGHAUS, a citizen of the United States, residing at Maywood, in the county of Cook and State of Illinois, have invented a new, original, and ornamental Design for a Tea-Kettle, of which the following is a specification, reference being had to the accompanying drawing, forming a part thereof.

The figure is a perspective view of a tea kettle showing my new design.

I claim:

The ornamental design for a tea kettle as shown.

WALTER LUTTRINGHAUS.
